(57) **CLAIM**

I claim the ornamental design for a toy for animals, as shown
and described.

DESCRIPTION

FIG. 1 is a top perspective view of the toy for animals
showing my new design;

FIG. 2 is a front view thereof;

FIG. 3 is a side elevation view thereof;

FIG. 4 is a bottom perspective view thereof;

FIG. 5 is a bottom view thereof;

FIG. 6 is another side elevation view thereof; and,

FIG. 7 is an end view thereof.
